Int. Cl. D7—01

U.S. Cl. D7—1

FIG. 1

FIG. 3

FIG. 1 is a top view of a disposable plastic dish showing my new design;

FIG. 2 is a bottom view thereof; and

FIG. 3 is a side view on an enlarged scale, partly in section, thereof.

The basket weave pattern shown in FIGS. 1, 2 and 3 extends about the full flange of the design.

This is a division of design application Ser. No. 222,428 filed Jan. 31, 1972 and now Pat. No. D. 229,812 dated Jan. 8, 1974.

I claim:

The ornamental design for a disposable plastic dish, as shown and described.
